UNITED STATES PATENT OFFICE

HEINRICH KLOTZ, OF WHEELING, WEST VIRGINIA

ELECTRICAL CONTROL MECHANISM

Application filed March 2, 1929. Serial No. 343,995.

This invention relates to power operated presses of the stamping or forming type, and has for one of the principal objects the provision of extremely simple and highly effective means of operation which permits the maximum amount of work with the minimum amount of effort on the part of the operator.

A further object of my present invention resides in a circuit with its associated mechanism for permitting the press to descend upon the work but a single time with each depression of the control switch. A still further object of my invention resides in the combination of the elements which may be readily applied to existing punch presses of various designs in a comparatively short time and after they have been placed in their operative position on the press they may be adjusted in the minimum amount of time.

The inventive idea involved is capable of receiving a variety of mechanical expressions, some of which for the purpose of illustration are shown in the accompanying drawings, but is it to be expressly understood that such drawings are for the purpose of illustration only and are not designed to define the limits of the invention, reference being had to the appended claims for this purpose.

In the drawing:

Figure 1 is a side elevation of a punch press, illustrated somewhat diagrammatically showing one embodiment of my invention as applied thereto;

Figure 2 is a wiring diagram thereof and

Figure 3 is a similar view but illustrating another embodiment of my invention.

My invention, in the form or embodiment shown in the drawing and briefly described, comprises a main solenoid, 10, an auxiliary solenoid, 11, a manually operated switch, 12, and a mechanically operated electrical closing device or switch, 13. The punch press which is indicated generally as at 14, may be of any well known type and is, of course, provided with the usual operating shaft, 15, for imparting reciprocating movement to the punch indicated as at 16.

In applying my invention to a press of the

usual type, I merely remove the ordinary foot operating mechanism and secure to the pivotally mounted link, 17, the arm, 18, through the medium of the adjustable link, 19. The arm, 18, is pivoted to a suitable lug, 20, which is carried by any convenient form of casing or housing, 21, secured to the side of the press in any desired manner. The casing, 21, is formed so as to conveniently house the solenoids, 10 and 11, together with their associated operating elements, as will be hereinafter more fully described.

The shaft 15 is provided on its periphery with a rounded lug or projection 22 for the purpose of contacting with the switch 13 after the press has been put into operation.

Referring now particularly to Figure 2 of the accompanying drawings, the main leads are indicated as at 23 and 24. Assuming that the manually operated switch 12 has been depressed for setting the punch in operation and assuming that the lead 23 is the positive wire, the current will flow through the switch 12 into the lead 25, passing through the switch arm 26 through the main solenoid 10 and through the lead 27 into the metallic plate 28 through the medium of the contact 29. The current now flows across the plate into the wire 30, through the medium of its contact 31 from which point it returns to the negative side of the line 24. This action forces the core 10' of the solenoid 10, downwardly into the solenoid and has effectually released the usual clutch (not shown) of the punch press through the medium of the arm 18, the link and arm 17 together with the connecting rod 17'. The punch press has now been set in motion and since it is highly desirable that it rotate but one revolution, reference is made to the following and further description.

It may be here stated that the core 10' is well into its solenoid 10, or sufficient to effectually operate the clutch of the press, as the pin 18' causes the disengagement of the arm 26 from the terminal contact 25', and thereby severing the main current from the solenoid 10. At this time, the current passes from the lead 25 through the shunt 100

43 to the solenoid 10. Obviously, but a small fraction of the current from the main line is utilized when it flows through the shunt 43.

5 The lug or projection 22 during its rotative movement depresses the pivotally mounted arm 13 sufficiently to make electrical connection between the upper end 32 of the arm 13 and the contact terminal 33 10 against the tension of the spring 34. The brief moment of contact between the end 32 of the arm 13 and the contact 33 is, of course, sufficient to cause the flow of current from the main lead 23 into the lead 36 which 15 terminates at the hub arm 13. The current now continues through the end 32 of the arm 13 and into the lead 37, passing through the auxiliary solenoid 11 and returns to the negative side of the line 24 through the medium of the short lead 38. This action 20 causes the drawing-in of the core 11' into its respective solenoid 11, and by reason of the fact that the metallic plate 28 is carried by the core 11', electrical contact is severed 25 between the plate 28 and the contact terminals 29 and 31 against the tension of the spring 39 and breaks the main circuit with respect to the solenoid 10.

Should the operator neglect to release 30 the switch 12, as for example, by failure to remove his foot therefrom, the following action occurs: Current continues to flow from the main lead 23 through the switch 12, thence through the lead 40 to the terminal 35 contact 41. From this point, it continues across the metallic plate 28, which is now in its lowered position and into the contact terminal 42, continuing to energize the solenoid 11 and to flow into the return lead 40 24 through the medium of the short lead 38. This action continues until the operator releases the manually operated switch 12.

When the switch 12 is released, the solenoid 11 is, of course, deenergized and permits the return of the metallic plate 28 to the contacts 29 and 31. The entire circuit is now open and the machine is ready for its repeated operation.

In the embodiment of my invention illustrated in Figure 3, I employ an electromagnet 44 and a pivotally mounted arm or armature 44' whose free end is arranged to be operated from the lug 22 of the shaft 15. In this form of my invention, when the 55 switch 12 has been closed, the current will flow from the lead 23 into the solenoid 10 through the medium of the lead 45, energizing this solenoid, the current returning to the main lead 24 through the medium of the arm 26, the lead 46, the contact terminals 47 and 49 through the medium of the metallic plate 48 and the return lead 50. This action, as in the form of my invention already described, causes the core 10' to be 60 drawn within the solenoid 10 and the down-

ward movement of the arm 18 depresses the switch arm 26 and permits the flow of current into the solenoid 10 through the medium of the shunt 43.

The shaft 15 is now released through the 70 medium of the clutch (not shown) and is caused to rotate in the direction shown by the dotted arrow. When the lug 22 contacts with the free end of the arm 44', the metallic plate 48 is moved away from the contact terminals 47 and 49 and causes the plate to form an electrical connection with respect to the terminals 53 and 54. Assuming, of course, that the switch 12 is still closed, the current from the lead 23 passes through the 75 magnet 44 through the medium of the lead 51 and leaving the magnet through the lead 52. The current now continues from the lead 53 through the metallic plate 48 into the terminal 54, from which point it is 80 directed to the lead 50 and back into the negative line 24.

As described in the previous embodiment of my invention, the several parts retain 85 this position until the switch 12 has been 90 released, at which time the various details will, of course, return to their initial position and be in readiness for its further operation.

From the above description, it will be 95 readily understood that this device will be effective in operation, continuously used at a very low up-keep with the minimum amount of fire hazards, due to the reduction of the intensity of the current, and one 100 which will require practically no adjustments after its installation.

I claim:—

105 Clutch operating mechanism comprising a lever pivotally mounted, a solenoid having a core engaged with said lever to move the lever in one direction when the solenoid is energized, an energizing circuit for said solenoid including a switch yieldingly held closed and disposed for engagement by said lever whereby the switch will be opened when the solenoid is energized, a manually controlled switch for closing said circuit, a shunt in said circuit paralleling the first 110 switch for passage of current to the solenoid when the switch is opened, a bridge in said circuit yieldably held closed, an auxiliary solenoid for moving the bridge to an open position when energized, an auxiliary circuit, for the auxiliary solenoid cut into 115 the first circuit having spaced contacts bridged by said bridge when the bridge is moved to break the circuit through the first solenoid, and a switch for the auxiliary circuit yieldably held open and adapted to be 120 closed when engaged by a portion of a rotating shaft of a machine.

In testimony whereof I hereunto affix my signature.

HEINRICH KLOTZ. 130
